(57) **CLAIM**

The ornamental design for a container with grip, as shown and described.

DESCRIPTION

FIG. 1 is an elevated front view of a container with grip according to the present invention;

FIG. 2 is a front view of a container with grip according to the present invention;

FIG. 3 is a back view of a container with grip according to the present invention;

FIG. 4 is a left side view (i.e. a view of the container of FIG. 2 rotated 90° to the right) of a container with grip according to the present invention;

FIG. 5 is a right side view of a container with grip according to the present invention;

FIG. 6 is a top view of a container with grip according to the present invention;

FIG. 7 is a bottom view of a container with grip according to the present invention;

FIG. 8 is an elevated perspective view of a container with grip according to the present invention taken by rotating the container of FIG. 1 about 30° to the right.;

FIG. 9 is an elevated perspective view of a container with grip according to the present invention taken by rotating the container of FIG. 1 about 45° to the right.;

FIG. 10 is an bottom elevational view of a container with grip according to the present invention;

FIG. 11 is a cross-sectional view of a container with grip according to the present invention taken along the line 11—11 of FIG. 2 and is shown to illustrate the contours of the container at the indicated position;

FIG. 12 is a cross-sectional view of a container with grip according to the present invention taken along the line 12—12 of FIG. 2 and is shown to illustrate the contours of the container at the indicated position;

FIG. 13 is a cross-sectional view of a container with grip according to the present invention taken along the line 13—13 of FIG. 2 and is shown to illustrate the contours of the container at the indicated position;

FIG. 14 is a cross-sectional view of a container with grip according to the present invention taken along the line 14—14 of FIG. 2 and is shown to illustrate the contours of the container at the indicated position; and,

FIG. 15 is a cross-sectional view of a container with grip according to the present invention taken along the line 15—15 of FIG. 2 and is shown to illustrate the contours of the container at the indicated position.

The broken line showing of a thread and of the top, inside edge of the pour spout is for illustrative purposes only and forms no part of the claimed design.
